UNITED STATES PATENT OFFICE.

HERMAN SENFTEN, OF LOS ANGELES, CALIFORNIA.

DESIGN FOR A CONTAINER.

58,689.

Specification for Design.

Patented Aug. 9, 1921.

Application filed April 5, 1920. Serial No. 373,017. Term of patent 7 years.

To all whom it may concern:

Be it known that I, HERMAN SENFTEN, a citizen of the Republic of Switzerland, residing in the city of Los Angeles, county of Los Angeles, and State of California, have invented a new, original, and ornamental Design for Containers, Especially for Candies, of which the following is a specification, reference being had to the accompanying drawing, forming part thereof.

Fig. 2 is a central vertical section of the same.

I claim:

The ornamental design for a container, as shown.

HERMAN SENFTEN.

In presence of:

STEPHEN MONTELEONE,
W. R. LITZENBERG.
